UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

CONSTRUCTION OF WINDOW FRAMES AND SASHES.

Application filed February 11, 1924. Serial No. 691,890.

To all whom it may concern:

Be it known that I, HARRY E. CAMPBELL, a citizen of the United States, and a resident of Baltimore, county of Baltimore 5 City, and State of Maryland, have invented certain new and useful Improvements in the Construction of Window Frames and Sashes, of which the following is a specification.

10 This invention has to do with windows of the sliding type, and relates particularly to the manner in which the sashes and frames are made.

For the purposes of illustration, I have 15 shown in the accompanying drawings, an application of my invention to the general type of window shown in certain of my earlier patents where plates projecting from the sides of the sashes extend into slots 20 formed in the inner wall of the jamb. In these drawings Fig. 1 is a sectional side view of a window embodying my invention; Fig. 2 is a section on line 2—2 of Fig. 1; Fig. 3 is a phantom view of an upper corner of 25 the frame with the pulley wheels removed; Fig. 4 is a phantom view of a lower corner of the frame; Figs. 5 and 7 are detailed views showing the manner in which the jamb is interlocked with the lintel and sill respectively; Fig. 6 is a detailed view showing 30 the manner in which the pulley wheels may be attached, and Fig. 8 is an elevation of a casting which may be used at the bottom of the baffle plate.

35 In the specimen window illustrated, the jamb is made up of a main box member 2, to which is attached a hook shaped member 3. The hook member 3 has a short leg 4, which forms a portion of the inner jamb

40 wall, and a longer leg 5 which forms a partition within the jamb so that member 3 may be considered both as a jam wall member and as a partition member. A baffle 6 is attached to leg 5 of member 3 and a sash guide 7 likewise is attached to leg 5. Both baffle 6 and guide 7 are provided with screw holes somewhat larger than the screws which are to go through them, so that these members may be adjusted in relation to leg 4.

45 A cover plate 8 interlocks with the edge of box 2 and fits into the hook end of guide 7. A weight separator 9 is attached to leg 5

but is made shorter than guide 7 and is provided with a keyhole opening 10 (see Fig. 1) by which it is hung in place. Both cover 55 plate 8 and separator 9 can be removed without disturbing the position of guide 7 or baffle 6 and therefore the weights 11 and 12 can be inserted without changing the adjustment of these parts.

60 The sill 13 has a vertical portion 14 extending substantially the width of the frame and has a flat horizontal portion 15 of the same length. The balance of the sill which is bent to form the groove 16, the ridge 17 65 and the ledge 18 is cut just long enough to contact at each end with a long leg 5 of member 3 (see Fig. 4). The short leg 4 of member 3 is cut to fit the incline of ledge 18. A sill bracket 19 is attached to 70 the underside of flat portion 15 of sill 13 and has a vertical portion 19' corresponding with portion 14 of the sill. Extending forward from flat portion 15 of sill 13, the bracket 19 is of sufficient width to contact 75 with the edge of the sill where it is bent down to form groove 16. The balance of the forward extension of bracket 19 is cut away just enough to allow leg 5 of member 3 to pass between the bracket and the sill 80 13. The ledge at the back of the slot thus formed is designated by the numeral 20.

85 At the time that member 3 is formed, there is cut or stamped in its rear edge a notch 21 (see Fig. 7) and this notch is so positioned that when leg 5 is pushed into place, the notch will engage ledge 20 thereby holding member 3 in correct position relative to sill 13. Box 2 is so shaped as to come down around the front and side of 90 bracket 19. Along the back where box 2 rests on sill 13 the joints may be strengthened by the use of an angle bracket 22.

95 In assembling a lower corner, bracket 19 and sill 13 are first secured together, and then leg 5 is pushed into place, with notch 21 engaging ledge 20. Member 3 is then secured, preferably by electrically welding the joint between leg 5 and bracket 19, for this joint would be out of sight when the 100 window is in use. Box 2 is then put in place and secured in any desired manner as by electric welding.

The lintel comprises a main lintel member

24 having a vertical side 25 and a slightly inclined side 26. The inclined side 26 is only of sufficient length to contact with legs 5 of members 3. Following the edge of the inclined side 26 is a slot 27. At the ends beyond the slots 27 the member 24 may be provided with flanges 28 to be bent down against the front of box 2 when the frame is finished (see Fig. 3).

10 Leg 5 of member 3 has near its top an opening cut in its rear edge to provide a place for one of the suspension pulleys, and at the upper corner of this opening there is formed a notch 29 which will interlock with main lintel member 24 when leg 5 is pushed into slot 27 (see Fig. 5). An opening 30 for the second pulley wheel is likewise formed in leg 5 near its top. The pulley wheels 31 and 32 may either be secured to leg 5 as shown in Fig. 8 or may be attached to the underside of lintel member 24. It may be noted that in the illustrative example a portion of baffle 7 is cut away to provide a space for pulley wheel 32 (see Figs. 2 and 3).

The lintel cover 34 has a vertical edge 35 to be secured to the side 25 of lintel member 24 and at its ends has downwardly bent flanges 36 which meet member 24. At the 30 corners outside of members 3, lintel cover 34 likewise has downwardly bent flanges 37 which meet member 24. The main portion of lintel cover 24 runs forward as shown at 38, so that the upper end of member 3 is 35 covered. This portion is then bent down as shown at 39 and then, an appropriate portion being cut away, is bent back at 40 and diagonally upward as at 41. The portions 40 and 41 are of such length as to have their 40 edges in contact with short leg of member 3.

The upper corners are assembled by first pushing leg 5 of member 3 into slot 27 of lintel 24 and securing these members in place preferably by electric welding. Box 2 is 45 then put in place and flange 28 is bent down and the joints secured in any desired manner as by welding. The pulley wheels 31 and 32 can then be fastened in position and finally cover 34 is put on and welded in place.

By the construction thus far described, I am assured that my window frame will be assembled with absolute accuracy, for the interlocking joints prevent any possibility of 55 slippage during the welding operation. In addition, the interlocking joints are formed within the jambs so that the parts which are thus connected may be enclosed by other frame members. It may further be noted that a frame thus constructed has a certain 60 degree of inherent rigidity, resulting from the manner in which the interlocking joints are formed, which exists independent of the permanent attachment of the members by welding or the like. This inherent rigidity

is due to the fact that at each corner member 3 which preferably is made of metal as heavy as 12 gauge bears against aligning portions of the member or members to which it is fastened. For example, at the lower 70 corners, each member 3 is held against being bent out beyond the position in which it will form a right angle with sill 13 by virtue of the fact that it will bear against the edge of bracket 19 and the edge of ledge 18 so 75 that when the two members 3 are held in parallel position, both must assume a position at right angles to the sill 13. In the same way, leg 5 of member 3 at the top bears against the upturned edge of portion 80 26 of lintel member 24. It is thus apparent that when a frame is fully assembled following this illustrative example, it does not depend solely upon the strength of the 85 welded joints for rigidity.

The sashes are of the general construction described in my earlier patents but embody certain novel features which are shown in Fig. 1.

Here it will be noted that the lift rail at the bottom of the lower sash is formed of three pieces in addition to the lift handle. The member 44 which is part of the main sash frame comes down outside of ridge 17 in the usual way. Inside of this is the glass stop 45 which preferably is bent in and down to form the hook 46. A member 47 is mounted against the glass stop 45 in such a way that its upper edge lies within the hook 46. The lower end of member 47 is bent in and down to fit into groove 16. In order that an exact fit may be obtained, the holes through which pass the screws that hold member 47 in place are made large enough so that they fit loosely about the screws. By this construction, member 47 can be moved up and down so that it can be adjusted to exactly the proper position in relation to the sill. The arrangement shown also provides a lift rail having a very desirable degree of 100 stiffness.

The meeting rail of the lower sash comprises a main sash frame member 50 and a glass stop 51 that is bent out and down as shown in Fig. 1. A zinc weather strip 52 bent to receive meeting rail member 53 of the upper sash is clamped entirely within the hooked portion of glass stop 51, instead of being brought around and fastened to the outside of glass stop 51 as formerly was done. The weather strip 52 is held in place by an angle clamp 54 which is attached to glass stop 51 by screws which pass down through the horizontal portion of the glass stop.

The top rail of the upper sash has a main sash member 55 and a glass stop 56 which is made S-shaped in cross section as shown in Fig. 1, thus providing a positive stop for upward movement of the upper sash. Fur- 130

ther, this gives stiffness to the top rail and also provides a place for a casting 57 having an opening 58 to receive the end of the usual window pole used to move the upper sash.

5. After the frame has been assembled in the manner heretofore described, the sashes are put in place, the weight chains are run through the pulleys and attached to the sashes; baffle 6 is then adjusted so that the 10 space between baffle 6 and the short hook 4 of member 3 will be just wide enough to permit the upper sash to move freely. In the same way sash guide 7 is then adjusted to give the proper clearance between its sash 15 guide and baffle 6 so that the lower sash can move freely but without rattling. Weight 11 can then be put in place and attached to the appropriate chain, and separator 9 can be attached in the manner which has already 20 been described. Thereupon weight 10 is inserted and attached to its chain and cover plate 8 is slipped into place and attached. It is obvious that cover plate 8 can at any 25 time be removed to give access to the weights, without disturbing the sashes or changing the adjustment of the openings in which they slide.

If desired, baffle 6 can run down to contact with ledge 18 of sill 13. I prefer, however, to insert a small casting shown in Fig. 8 which permits me to square the lower end of baffle 6 so that both the baffles for a given window can be made identical, instead of demanding the necessity of making right 35 and left hand members. The casting shown in Fig. 8 which is designated by numeral 60 has its lower surface sloped to conform with the pitch of ledge 18. The upper surface has a portion 61 which will lie horizontal when the casting is in place, and an extension surface 62 which may slope up slightly to give the casting strength. The front of the casting corresponding to the portion 62 is cut away to receive the short 40 leg 4 of member 3. On the top of the casting there is provided a lug 63 which will serve as a stop to limit downward movement of the upper sash. This casting is simply 45 dropped into place before the baffle 6 is attached and will be held in place by baffle 6.

It is to be understood that the foregoing example is intended for the purposes of illustration only and that the same may be modified in many particulars without departing 50 from the spirit of my invention.

What I claim is:

1. A window frame comprising a sill member, a lintel member, jambs, each of which comprises a partition member, interlocking joints formed between said partition members and the sill and lintel members, and a casing surrounding each of said joints.

2. A window frame comprising in combination, a lintel and a sill, each of sheet metal,

a jamb member of sheet metal adapted to interlock with the sill and with the lintel, and a member at each corner of the window frame connected with one of the interlocked members tending to hold the interlocked members at a right angle.

3. A window frame comprising in combination, a lintel and a sill, a jamb member on each side of the window frame having a portion adapted to stand within the jamb, and interlocked joints between each such member and the sill and lintel respectively, formed intermediate the planes of the front and rear jamb walls.

4. A sheet metal window frame comprising two jambs, a sill and a lintel, interlocking joints between said members at the corners of the frame adapted to cause the members of each pair of interlocked members to assume positions at right angles to each other, and additional means for holding said members in interlocked position.

5. The method of building a window frame which comprises the steps of fabricating the sill and lintel, each with notches spaced apart an equal distance, fabricating two corresponding jamb members each with notches spaced apart an equal distance and so positioned as to be removed from the line of the final jamb wall, interlocking said notches to form a rectangular frame, welding the interlocked members together, and building up the jamb walls about said jamb members.

6. A window frame and sash construction comprising two sashes, jambs having openings in their inner faces in which the sashes slide, means for adjusting the width of said openings, counterbalance weights for the sashes within the jambs and a cover plate forming part of the inner face of each jamb at one side of and distinct from the jamb parts which define said openings, which cover plates are removable to give access to said weights without changing the adjustment of the jamb members which define said openings.

7. A structure as defined in claim 6 in which each jamb contains two weights between which is a weight separator which may be removed without changing the adjustment of the jamb members which define the opening in the jamb face.

8. A window-frame and sash construction, comprising jambs, sashes adapted to slide in the jambs, means for adjusting the clearance between the sashes and the jambs, a weight compartment in each of the jambs and a removable plate admitting to each such weight compartment and forming a portion of the inner face of each jamb, such plates being removable without changing the adjustment of the clearances between the sashes and the jambs, and so positioned that they do not contact with the sashes when the

window is closed and may be removed after the window has been built into a finished wall.

9. In a window frame and sash construction, the combination of a sill and a sash having a main sash frame member adapted to contact with said sill and support a seat for the lower edge of a pane of glass, a member adjustable in relation to said main sash frame member adapted to contact with the sill and a glass stop having its upper edge bent over and down to cover the edge of said adjustable member.

10. In a window frame and sash construction, the combination of two hook-shaped meeting rail members, a relatively flexible weather strip within one of said hooks

shaped to receive the other hook and a clamping strip within said first hook to hold said weather strip in place.

20

11. In a window frame and sash construction, the combination of a lintel having an opening to receive a sash member, a main sash frame member adapted to enter said opening and a glass stop of S-shaped cross section attached to such main member, with its lower opening turned away from the main member and so positioned as to contact with the lintel to limit upward movement of the sash.

25

12. A structure as defined in claim 11 provided with a pole socket in the lower opening of said glass stop.

HARRY E. CAMPBELL.
